UNITED STATES PATENT OFFICE.

WENDELIN P. SENG AND DARREL FRANK DYKE, OF CHICAGO, ILLINOIS, ASSIGNEES TO
DAVOPLANE BED COMPANY, OF CHICAGO, ILLINOIS, A CORPORATION OF ILLINOIS.

SOFA-BED.

1,136,173.

Specification of Letters Patent. Patented Apr. 20, 1915.

Application filed July 3, 1912. Serial No. 707,443.

To all whom it may concern:

Be it known that we, WENDELIN P. SENG and DARREL FRANK DYKE, citizens of the United States of America, and residents of 5 Chicago, county of Cook, and State of Illinois, have invented certain new and useful Improvements in Sofa-Beds, of which the following is a specification.

The main objects of this invention are to 10 provide an improved form of sofa-bed comprising a plurality of bed sections hinged together and supported on a base and adapted to be folded one upon the other onto said base, whereby the sofa-bed is adapted for 15 use as a sofa, and adapted to be extended in substantially horizontal alinement for use as a bed; to provide a sofa-bed wherein the bed sections are adapted to be folded into compact form so as to occupy the minimum 20 amount of space when converted into a sofa, and to be extended to form a bed affording the usual amount of bed surface; to provide an improved method of securing the sections to the supporting base whereby they 25 may be quickly placed upon and removed from said supporting base; to provide an improved arrangement of the bed sections whereby they may be folded with the mattress and bedding in normal position there- 30 on; to provide improved means for successively locking the sections together as they are folded upon each other; to provide a sofa-bed in which the several bed sections are attached to the under side of a seat 35 frame invertibly mounted on said supporting base; to provide improved means for securing the bed sections in their folded positions on said seat frame; to provide improved means for securing said seat frame 40 in its inverted position; and to provide an improved sofa-bed of this kind, which, when the sections are extended for use as a bed, has the length of the bed disposed transversely to that of the sofa. 45 An illustrative embodiment of this invention is shown in the accompanying drawings, in which:

Figure 1 is a plan view of a sofa-bed constructed according to this invention with 50 the parts in position for use as a bed. Fig. 2 is a transverse elevation taken on the line A—A of Fig. 1 showing the parts in their folded positions for use as a sofa. Fig. 3 is a similar view showing the seat frame 55 inverted on the supporting base prepara-

tory to extending the sections for use as a bed, the mattress and bedding being indicated in dotted outline. Fig. 4 is a side elevation taken on the line A—A of Fig. 1 showing the parts in their extended position for use as a bed. Fig. 5 is a fragmentary side elevation of the sections illustrating different steps in the folding or unfolding thereof. Fig. 6 is a similar view showing still another step in the folding of 60 the sections. Fig. 7 is a fragmentary sectional detail illustrating the mechanism by which the seat frame is locked to the base when in its inverted position. Fig. 8 is an enlarged fragmentary detail illustrating the 65 manner in which the opposite movement of the locking rods is accomplished.

In the construction shown in the drawings the sofa-bed comprises the usual supporting base having ends 1 and 2 and back 75 3, which as a whole constitutes the supporting base and housing for the seat frame and bed sections. The seat frame 4 is tiltably or rotatably mounted between the ends 1 and 2, and has one side thereof upholstered 80 to form a sofa seat 5. At the other side of the seat frame 4 the several bed sections are connected, onto which they are adapted to be folded.

The connection of the seat frame 4 to the 85 supporting base comprises pairs of plates 6 and 7 respectively secured to the ends 1 and 2 of the base and to the seat frame 4. These plates are respectively provided with slots 8 and 9 with which coact pins 90 10 and 11 respectively secured on the plates 6 and 7. The relative shape and disposition of the slots 8 and 9, and the location of the pins 10 and 11, are such that the seat frame 4 may be inverted by reason of the shifting 95 pivotal action taking place between the seat frame 4 and the base through the coaction of the pins and slots. The plates 6 and 7 are respectively provided with shoulders 12 and 13 which are arranged so as to have interlocking engagement when the seat frame is 100 shifted to its normal or sofa position.

The bed comprises three comparatively wide sections and two comparatively narrow sections, alternately hinged together 105 and adapted to be folded onto the under side of the seat frame 4 with the three wide sections lying in substantially horizontally parallel planes, and the narrow sections vertically disposed at the opposite edges there- 110

of. Brackets 14 are secured to the ends of the seat frame 4 adjacent to what would be the rear edge of the seat frame when in the sofa position. Notches 15 are formed 5 in the ends thereof, in which are received the pins 16 secured to the ends of the narrow bed section 17 intermediate the edges thereof. The connection of the bed section 17 to the bracket 14 is such that it may 10 swing from a substantially vertical position to a substantially horizontal position. The inner wide bed section 18 and the middle wide bed section 19 are hinged to the section 17 at opposite sides thereof. The section 15 18 is designed to be shifted from a lowered position on said seat frame to an elevated position and vice versa respectively with the shifting of the narrow section 17 into and out of its horizontally disposed position. 20

The elevating or lowering of the section 18 is accomplished by means of plates 20 located forwardly of the brackets 14 at the ends of the seat frame 4. Each bracket is 25 provided with an inclined cam surface 21 on which the pins, secured to the section 18 ride. Each of the cam surfaces 21 terminates at its upper end in a horizontally disposed surface 23 on which the pins 22 rest 30 when the section 18 is shifted to its elevated position, and at its lower end terminates in a hook 24 which coacts with its respective pin 22 for securing the section 18 in its lowered position. The section 17 is further 35 braced and secured to the supporting brackets 14 by means of a brace 25 connected at its ends to the ends of the section 17 and at several intermediate points, to an angle iron 26 secured along the rear edge of the 40 seat frame 4, as by bolts and nuts (not shown). An additional narrow section 27 and the outer wide section 28 are hinged together and to the section 19, and are adapted to be extended in horizontal alignment 45 with the other sections, or to be folded therewith onto the seat frame with the wide section 28 in between the sections 18 and 19, as indicated in Figs. 2 and 3.

The sections 18 and 19 are of substantially 50 the same width, and the section 28 is somewhat narrower than the sections 18 and 19 so that it may be folded in between them, the difference in width being substantially equal to the thickness of the mattress and 55 the usual bedding. The sections 17 and 27 are also of different widths, the difference being a little more than the thickness of the mattress and bedding the width of the wider section being a little more than three folds 60 of the mattress and bedding, and that of the section 27 being substantially equal to two folds of the mattress and bedding.

The sections are supported in their horizontally extended positions by means of 65 pairs of legs 29 and 30 respectively pivoted

at 31 and 32 on the ends of sections 19 and 28 adjacent to the forward edges thereof. The legs of each pair are extended upwardly beyond their pivots and have the pairs of links 33 and 34 respectively connected thereto, and to the sections 17 and 27, whereby the legs are caused to automatically shift to positions transversely of the sections when unfolded and substantially parallel therewith when the sections are folded. 70 The narrow section 27 is braced by a rod 35 connected at its ends to the pivotal connection of the links 34. 75

The sections 19 and 28 are locked together 80 when folded upon each other and these sections are locked to the seat frame when folded upon the section 18. The mechanism for locking the sections 19 and 28 together comprises dogs or pawls 36 pivotally connected on the ends of the section 28 inwardly 85 of the pivotal connection of the legs 30 thereto. The pawls are provided with notches or recesses 37 which are adapted to engage shoulders or projections 38 located on the ends of the section 19. Pins 39 on the 90 links 34 engage recesses 40 in the pawls 36, which during the shifting of the legs 30, shift the pawls into and out of position for causing the engagement of the recesses 37 and shoulders or projections 38. The pawls 36 are provided with inclined shoulders 41 which coact with the shoulders or projections 38 for directing the pawl to insure the engagement of the recesses 37 therewith. The pawls 36 are locked, when in engaging 95 position with the section 19, by means of pins or shoulders 42 carried on the inner side of the legs 29 and so positioned that when the legs are shifted to their folded positions, through the folding of the sections, the pins 42 will engage the edge of the pawls opposite the recesses 37. It is then impossible for the pawls to release the sections until they are shifted so as to unfold the legs 29 and retract the pins 42. The 100 locking of the bed sections to the seat frame when in their folded positions is accomplished by means of a rod 43 rotatably mounted in clips 44 on the inner face of the 105 front rail 45 of the seat frame, which rod 43 is provided at its upper end with a transversely disposed shoulder 46 that is adapted to be shifted to the position shown in Fig. 3 for engaging and locking the folded sections 110 to the seat frame. The rod 43 is connected 115 by a transverse bar 47 to the rods 48 and 49 slidably mounted on the front rail or panel 45 of the seat frame. The rods 48 and 49 are so arranged as to have their outer ends shifted into recesses 50 located in an adjacent part of the ends 1 and 2, for the purpose of locking the seat frame 4 in its inverted position, when the rod 43 is shifted 120 to disengage the shoulder 46 from the folded 125 bed sections.

The front rail or panel 45 is made of sufficient width to hide the bed sections when the seat frame is in its normal sofa position.

The operation of the device is as follows:

- 5 If it is desired to extend the sofa bed for use as a bed, the seat frame 4 is first shifted to an inverted position. This is accomplished by elevating the front thereof, whereupon the pins 10 and 11 shift in the 10 slots 8 and 9 and cause the seat frame 4 to assume the position in which it is shown in Figs. 3 and 4. The rod 43 is then turned so as to disengage the shoulder 46 from the bed sections, which shifts the rods 48 and 49 15 and causes the ends thereof to engage the recesses 50, thereby locking the seat frame in its inverted position. The operator then grasps the rod or brace 35 and pulls the sections upwardly and outwardly to the position 20 shown in full outlines in Fig. 5. This movement of the section swings the section 17 on its pivot to a horizontally disposed position which causes the section 18 to shift rearwardly and forces the pins 22 along the inclined surfaces 21 of the plates 20 and onto the transversely disposed surfaces 23, so that the section is elevated to and supported in its horizontally disposed position. This same movement of the sections 25 also causes the links 33 to unfold the legs 29, and the unfolding of the legs withdraws the pins 42 from the pawls 36. In order to unfold the sections 27 and 28 from the position shown in Fig. 5, it is first necessary for the operator to grasp the ends of 30 both legs 30 and elevate them slightly. This movement of the legs causes the pins 39 to retract the pawls 36 and thereby disengage the recesses 37 from the pins 38, whereupon 35 the sections 27 and 28 may be shifted to their horizontally extended positions, as shown in Fig. 4. The unfolding of the sections 27 and 28 also causes the legs 30 to be unfolded to a transverse position for 40 supporting the section 28. The sofa-bed is 45 then ready for use as a bed.

When it is desired to fold the bed sections to reconvert into a sofa, the outer section 28 is folded upon the section 19. This folding 50 of the sections causes the pins 39, working in the slots 40, to shift the pawls 36 into position to engage the shoulders or projections 38. These sections are then folded upon the innermost section 18. During the 55 movement of the sections from the position shown in Fig. 5 to that shown in Fig. 6, the legs 29 are caused to shift to their folded positions, whereupon the pins 42 engage the edges of the pawls 36 for securing the pawls 60 against becoming accidentally disengaged from the shoulders or projections 38. During the movement of the sections from the position shown in Fig. 6 to that shown in Fig. 3, the section 17 swings on its pivot 65 from a horizontal to a vertical position,

thereby pulling the section 18 forwardly and causing the pins 22 to descend their respective inclines 21 and engage the hooks 24. When the sections are thus folded they are locked to the seat frame by turning the rod 43 to shift the shoulder 46 over the adjacent edge of the folded sections. This movement of the rod 43 shifts the rods 48 and 49 so as to disengage them from the recesses 50, whereupon the seat frame may 70 be shifted to its normal position for use as a sofa. 75

Although but one specific embodiment of this invention has been herein shown and described, it will be understood that numerous details of the construction shown may be altered or omitted without departing from the spirit of this invention as defined by the following claims. 80

We claim:—

1. In a sofa bed, the combination of a pair of wide bed sections and an intermediate narrow section foldably hinged together, engaging means on said wide sections adapted to have interlocking engagement when said sections are shifted to their folded positions, and other means adapted to be so shifted through the folding of said sections as to lock aforesaid engaging means when interlocked. 85

2. In a sofa bed, the combination of a pair of wide bed sections and an intermediate narrow section foldably hinged together; a shoulder on one of said wide sections; a pawl pivotally carried on the other of said wide sections and having a notch therein adapted to engage said shoulder when said sections are shifted to their folded positions, and means adapted to be automatically shifted, through the folding of said sections, into 100 position to lock aforesaid pawl in engagement with said shoulder. 105

3. In a sofa bed, the combination of a supporting frame; a pair of wide bed sections and an intermediate narrow section foldably hinged together; a shoulder on one of said wide sections; a pawl carried on the other said wide section and having a notch therein adapted to engage said shoulder when said wide sections are folded; a leg pivotally 110 connected to said one wide section; a link so connected to said leg as to control the shifting thereof to cause it to occupy a position transversely to said sections when extended and substantially parallel thereto when said sections are folded; and a shoulder carried on said leg and adapted to engage said pawl when said sections are shifted to their folded positions and to lock said pawl in engagement with said shoulder. 115

4. In a sofa bed, the combination of a supporting frame; a pair of wide bed sections and an intermediate narrow section foldably hinged together; a shoulder on one of said wide sections; a pawl carried on the 120 125 130

other said wide section and having a notch therein adapted to engage said shoulder when said wide sections are folded; a leg pivotally connected to said other section; a link connected to said leg and to said narrow section and adapted to shift said leg to a position transversely of said sections when extended and into a substantially parallel position therewith when folded; and a 5 shoulder carried by said link and adapted to engage said pawl and so control the movement thereof as to cause said pawl to engage said shoulder when said sections are folded to their parallel positions.

10 5. In a sofa bed, the combination of a supporting frame; a pair of wide bed sections and an intermediate narrow section foldably hinged together; a shoulder on one of said wide sections; a pawl carried on the other said wide section and having a notch therein adapted to engage said shoulder when said wide sections are folded; a leg pivotally connected to said other wide section; a link connected to said leg and to said 15 narrow section and adapted to shift said leg to a position transversely of said sections when extended and into a substantially parallel position therewith when folded; a shoulder carried by said link and adapted 20 to engage said pawl and so control the movement thereof as to cause said pawl to engage the first mentioned shoulder when said sections are folded to their parallel positions; a second leg pivotally connected to said first 25 mentioned wide section; a link so connected to said second leg as to shift the same to cause it to occupy a position transversely of said one section when unfolded and to occupy a position substantially parallel therewith when said sections are folded; and a 30 shoulder carried by said second leg and adapted to engage said pawl when said sections are folded, and to lock aforesaid pawl in its engaged position with said first mentioned shoulder.

35 6. In combination, a plurality of foldable sections, a catch-member pivoted to one section and a second section having a part with which said catch-member engages when the

sections are in folded relation, and means 50 pivoted to one of said sections in spaced relation to the pivot of the catch-member and operable when moved relative thereto to impart a releasing movement to said catch-member.

55

7. In combination, a plurality of foldable bed frame sections, a leg pivoted to one of said sections, and a section locking device pivoted to the aforesaid section and automatically operable to lock two sections together upon a folding of one over the other and operable by an unfolding movement of the leg to release the locking connection between said sections.

60

8. In combination, a set of hingedly connected frame parts, one being foldable over the other, a latch member and a leg each pivoted to one of said sections and the latch member being adapted to lock the sections in folded relation and being operable by an unfolding movement of the leg to release the locking connection between said sections.

65

9. In combination, a plurality of foldable bed frame sections, a leg pivoted to one of said sections, and a section locking device 70 carried by the section with said leg and controlled by a movement of the leg and also acting on the leg to yieldingly retain it in folded position relative to its carrying section.

75

10. In combination, a plurality of foldable bed frame sections, a leg pivoted to one of said sections, a catch member yieldingly carried by one section for yielding movements relative thereto and adapted to engage a part of another section to retain the sections in folded relation, said catch member also being operable to yieldingly retain the leg in folded position relative to its carrying section.
